(57) **CLAIM**

The ornamental design for an aerial toy, as shown and described.

DESCRIPTION

FIG. 1 is a perspective view of an example aerial toy according to my invention;

FIG. 2 is a right side plan view thereof, the left side plan view being a mirror image thereof;

FIG. 3 is a top view thereof;

FIG. 4 is a bottom view thereof;

FIG. 5 is a rear view thereof; and,

FIG. 6 is a front view thereof.

The broken line showings of FIGS. 1-6 represent claimed boundaries only (shown in dash-dot lines) and environmental subject matter only (shown in single dashed lines) and form no part of the claimed design.
